(57) CLAIM

I claim the ornamental design for a fabric with pattern, as shown and described.

DESCRIPTION
